UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

ACETYLENE LAMP.

1,424,463.

Specification of Letters Patent. Patented Aug. 1, 1922.

Application filed May 11, 1921. Serial No. 468,546.

To all whom it may concern:

Be it known that I, WILLIAM J. FRISBIE, a citizen of the United States, and a resident of Chicago, in the county of Cook, State of Illinois, have invented certain new and useful Improvements in Acetylene Lamps, of which the following is a specification.

My invention relates to acetylene lamps, particularly miners' acetylene cap lamps and 10 the object is to provide improved means for securing the lamp supporting clamp thereto.

These miners' acetylene cap lamps are usually supported on a plate secured on the cap, the lamp having a hook for engaging in a 15 hole provided in the plate and having also a clamping frame or arms for clampingly engaging around the sides of the plate, the lamp being thus rigidly supported. The practice heretofore has been to secure the 20 clamping frame or arms by means of solder against the outer face of the lamp. The disadvantage of this practice is that the solder, being soft, will yield readily to abnormal pressure and the arms or frame can be readily 25 torn from the lamp. Another disadvantage is that the solder gives an unsightly appearance to the lamps as it soon tarnishes.

My invention eliminates the above disadvantages. In accordance with my arrangement I insert the inner ends of the clamping arms or the yoke section of a clamping frame behind a section of sheet metal on the lamp, or between metal sections or walls of 35 the lamp, to be thus mechanically clamped and further secured if desired by means of soldering, such soldering however being on the inside so that it will not be visible at the exterior of the lamp. This so securely 40 fastens the arms or frame to the lamp that it will be impossible to pull off an arm except by breaking it. The arrangement also eliminates solder on the outside of the lamp and gives it a neater and more practical appearance.

The various features of my invention are shown on the accompanying drawing in which—

Fig. 1 is a side elevational view of a 50 miner's cap lamp,

Fig. 2 is a rear elevational view of the water container part of the lamp,

Fig. 3 is a plan view of the structure shown in Fig. 2, with the bottom member

thereof removed and with the supporting 55 clamp placed in position,

Fig. 4 is a plan view similar to Fig. 3 showing the bottom member in place to clamp the clamping frame,

Fig. 5 is a sectional view on plane 5—5, 60 Fig. 4,

Fig. 6 is a side elevational view similar to Fig. 2 showing a modified arrangement and

Fig. 7 is a sectional view on plane 7—7 65 Fig. 6.

The lamp shown comprises the water container structure A and the carbide cup B. The water container comprises the cylindrical body part 10, the top 11, and the 70 socket shaped member 12 which forms the bottom of the container. As shown, the lower section 13 of the body part 10 is concaved or drawn inwardly a distance to receive the socket member 12 which is threaded for receiving the upper threaded section 14 of the carbide cup B, as well understood 75 in the art.

Extending through the top 11 and through the lamp is the valve stem 15 controllable 80 by the lever 16, and the plug 17 normally closes the water filler opening 18.

Secured to the back of the water container body is the hook 19 which engages in the hole of the lamp supporting plate (not 85 shown) on miners' caps. On the front side of the water container is supported the reflector 20.

In Figs. 1 to 5 F represents the spring clamping frame comprising the yoke section 21 and the arms 22 extending outwardly from the ends thereof, the arms at their ends being deflected to form the notches 23 which receive the edges of the plate on the miner's cap, such clamping engagement 95 of the arms together with the engagement of the hook 19 with the plate rigidly anchoring the lamp on the cap plate. In accordance with my invention I provide the holes 24 and 25 in the wall 13 and the frame 100 F is inserted through the holes to bring its yoke section 21 inside of the wall 13 as clearly shown in Fig. 3. The yoke section 21 is curved to almost clear the opening surrounded by the wall 13 and to overhang 105 just sufficiently to be engaged by the threads of the socket member 12 which forms the bottom of the water container. When this

socket member is then inserted its threads will engage with the yoke section of the clamping frame and will exert pressure thereon, such pressure mechanically anchoring 5 the clamping frame in proper position (Fig. 4). Solder is then run around the space between the wall 13 and the side wall of the socket member 12 and the socket member is securely soldered in place to form 10 the bottom of the water container. The solder also fills the holes 24 and 25 around the clamping frame and the solder also secures the yoke section 21 of the frame to the adjacent walls. The water container is thus 15 sealed and the frame rigidly secured by being mechanically clamped between the walls 12 and 13 as well as being soldered there-to. The sheet metal of the lamp prevents any strain on the clamping frame arms from 20 tearing or loosening the solder and the arms can be removed only by bending thereof until they break. Furthermore the lamp presents a much more sightly and neat appearance as the only solder which will show on 25 the outside is perhaps a little bit at the holes through which the clamp frame extends. A special soldering operation is also avoided as the clamp is soldered in place at the same time that the socket section 30 12 is secured to the water container body.

In Figs. 6 and 7 I have shown a modified arrangement. Here, separate clamping arm members 26 and 27 are used, and the wall section 13 of the lamp has the outward deflection or embossment 28 into whose ends 35 the inner sections of the arms may be inserted as shown in Fig. 7. The arms are inserted after the socket member 12 has been inserted and the arm ends will then be 40 clamped between the socket member and the wall section 13, and then when solder is run around in the space between the parts 45 12 and 13 the arms will be securely and rigidly held in their proper clamping position.

I thus provide a practical, neat and efficient means for securely fastening clamp-arms or frames to miners' acetylene cap lamps. I claim as follows:

50 1. In a miner's acetylene lamp, the combination with the water container body, of a bottom member therefor, a supporting structure, extending from said container body, said body having an opening, the inner end of said supporting structure ex-

tending through said opening to be received between the body wall and said bottom structure to be thus held in position.

2. In a miner's acetylene cap lamp, the combination with the sheet metal body part 60 of the water container for the lamp, a bottom member extending upwardly into said body part, a U-shaped clamp frame, the yoke of said frame being inside of said body part and clamped between the walls 65 of said body part and the bottom member.

3. In a miner's acetylene cap lamp, the combination of the sheet metal water container body, a carbide cup receiving socket extended into said body to form the bottom 70 of the water container, a U-shaped clamping frame of spring metal having its yoke section extended into said body to be in the path of said socket member when inserted and to be thereby clamped between the 75 socket member and the body, the outer ends of said frame forming clamping arms.

4. In a miner's acetylene cap lamp, the combination of the water container part and the carbide cup, the carbide cup having 80 a threaded neck, the water container part comprising a body part of sheet metal and a socket part extended into the lower end of said body part and threaded to receive the threaded neck of the carbide cup, a U-shaped 85 clamping frame of spring metal having its yoke section within the body part and projected a distance into the path of said socket part when inserted into the body part whereby said socket part will engage with said 90 yoke section and spring it to thereby clamp it between the socket part and the body part, said body part having holes, the ends of said frame extending through said holes to the outside of the body part and provided 95 at their ends with clamping notches.

5. In a miner's acetylene lamp, the combination with the sheet metal body having holes therethrough, of an inner frame inserted into said body to be parallel with the 100 sides thereof, and a supporting structure extending from the container body, the inner part of said supporting structure extending through said holes to be received between the body wall and the adjacent wall 105 of the inner frame to be thus held in position.

In witness whereof, I hereunto subscribe my name this 9th day of May, A. D. 1921.

WILLIAM J. FRISBIE.
